UNITED STATES PATENT OFFICE.

AUSTIN O. STANLEY, OF DETROIT, MICHIGAN.

SPEED-INCREASING MEANS FOR BOATS.

Application filed April 2, 1925. Serial No. 20,063.

This invention relates to means for increasing the speed of boats of all sizes by diminishing the frictional resistance offered by the water through the creation of a suction and oblique currents adjacent the bow and sides of the boat, and by utilizing the driving power of the water eddying in to fill the suction so created.

The principal object of my invention is the provision of mechanism carried by a boat for receiving water from in front of the boat and expelling the water forcibly and in laterally oblique directions just rearwardly of the bow to thereby create currents tending to move away from the sides of the boat the water that would ordinarily form a resistance to the passage of the boat therethrough. Currents of water moving substantially in the same direction as the boat then eddy in to replace the water driven away from the bow and sides of the boat and tend to sweep the vessel forwardly, whereby the boat is moved ahead faster than it would be driven by its propeller acting alone.

Another object of my invention is the arrangement of pumps and outlet pipes adjacent the bow of the boat whereby water will be expelled at both sides of the vessel in a series of jets extending from the water line to adjacent the lowermost portion of the boat.

Other objects and advantages will be apparent from the following description, wherein reference is made to the accompanying drawings illustrating a preferred embodiment of my invention and wherein similar reference numerals designate similar parts throughout the several views.

In the drawings:

Fig. 1 is a side elevation of a vessel equipped with my improved speed increasing means.

Fig. 2 is an enlarged detail elevation of the bow portion, and showing the arrangement of the inlet pipe and outlet pipes of my improved apparatus at one side of the vessel.

Fig. 3 is a detail cross section taken substantially on the line 3-3 of Fig. 2, and

Fig. 4 is a detail section taken substantially on the line 4-4 of Fig. 1.

Referring now to the drawings, the numeral 5 designates a vessel of any desired size and contour equipped with some form of propelling means herein shown as a pro-

peller 6 arranged adjacent the rear of the boat. It will be understood that the showing in Fig. 1 is merely for purposes of exemplification, and that my improved speed increasing means is adapted for use with vessels equipped with any desired type of propelling means, utilizing manual or wind power or various forms of engines or turbines to drive mechanically actuated propelling devices. The propeller 6 herein shown is adapted to move the vessel at a predetermined rate of speed when my improved speed increasing means is not in operation, and it is to be understood that the propeller aids at all times in the propulsion of the boat and that my improved apparatus is auxiliary to the usual propelling means of the vessel.

My improved speed increasing means will now be described: At the forward extremity of the vessel is mounted a pump 7 of any desired type adapted to receive water from in front of the vessel through the inlet pipe 8 and expel such water through a plurality of outlet pipes 9 and 10 arranged on both sides of the vessel. The outlet pipes are preferably provided with nozzles 9^a and 10^a extending from adjacent the water line to adjacent the lowermost portion of the vessel substantially as shown in Fig. 1, such nozzles being preferably shaped to closely parallel the sides of the vessel. Each nozzle is herein shown as provided with a plurality of spaced apertures 9^b and 10^b through which the water from the pump is directed outwardly in a series of jets adjacent the entire submerged portion of the vessel. These apertures are so located in the nozzles 9 and 10 that the water issuing therefrom will be directed rearwardly of the boat and in divergent streams angularly away from the longitudinal axis of the boat. The arrows in Fig. 3 illustrate the movement of the water issuing from the apertures 9^b and 10^b in the nozzles 9 and 10. These streams of water forcibly ejected from the several jets in the nozzles on both sides of the vessel will set in motion the water adjacent the sides of the vessel that would ordinarily form a resistance to the passage of the vessel therethrough, and tends to move such otherwise resisting water away from the sides of the vessel so as to form a suction adjacent the forward portion of the boat, or at least the major portion thereof, into which vacuum the vessel

is moving with diminished frictional resistance. The water adjacent the rear half of the vessel tends to eddy into the vacuum thus formed by the divergent outward movement of the water at the forward half of the vessel, and in so doing moves substantially in the same direction as the boat, and accordingly, sweeps the boat forwardly with it with a force that works in addition to the usual driving force of the propeller 6. The pump 7 is herein shown as of the centrifugal type with the inlet pipe 8 dividing into two portions 8^a and 8^b leading respectively to the ends of the pump portion, while the outlet pipes are shown as leading from the periphery of the pump casing adjacent its ends. A portion of the issuing water is directed through the relatively small pipes 10 to the sides of the vessel closely adjacent the foremost point of the boat while the major portion of the water issuing from the pump is directed through the larger pipes 9 to the sides of the boat more nearly adjacent the widest portion of the boat. In this manner currents are set up in the surrounding water to move away the otherwise resisting water from all the forward portion of the boat except that relatively small portion between the nozzles 10^a and the foremost point of the boat. The water issuing from the smaller nozzles 10^a diverge from the longitudinal axis of the boat at a greater angle than does the water issuing from the larger nozzles 9^a, as best shown in Fig. 3. This permits the smaller nozzles to set in motion the water adjacent the bow of the boat so that it is in motion away from the sides of the boat when it is later impinged by the water issuing from the larger nozzles 9^a after the boat has moved forward under the impulse of the propeller 6 and the eddying currents hereinbefore referred to. The larger volume of water issuing from the nozzles 9^a adjacent the wider portion of the vessel serves to set in motion that larger body of water that would be contacted by the wider portion of the vessel and it has been found that such larger body of water is more readily moved when the divergent currents set up by the smaller nozzles 10^a have started the flow of adjacent water away from the sides of the vessel. As herein shown I have provided a protective covering 11 to prevent the resistant water from damaging the outlet pipes 9 and 10, and suitable elongated apertures 12 and 13 are provided in this protective covering for the issuance of the water from the nozzles 9^a and 10^a respectively. These apertures 12 and 13 are directed toward the rear of the boat and permit the outflow of the pumped water in the desired directions, while the outermost walls of such apertures are arranged to divert the resistant water from the nozzles.

As best shown in Figs. 2 and 4, I also provide apertures 14 adjacent the lower portion of the protective covering 11 to admit water to the interior of the protective casing so that the issuing water will carry with it a substantially solid body of water. Vanes 15 are preferably arranged directly above the apertures 14 to utilize the water coming through the apertures 14 to lift the bow of the vessel. 70 75

While it will be apparent that the illustrated embodiment of my invention herein disclosed is well calculated to adequately fulfill the objects and advantages primarily stated, it is to be understood that the invention is susceptible to variation, modification and change within the spirit and scope of the subjoined claims. 80

Having described my invention, I claim—

1. In combination with a vessel having a main propelling means, speed increasing means for the vessel including a pump mounted on the vessel, an intake pipe for the pump arranged to receive water from in front of the vessel, and outlet pipes extending below the water line rearwardly of the bow of the vessel and arranged to expel the water from the pump in divergent streams directed rearwardly of the vessel, said outlet pipes being provided with a plurality of spaced apertures for directing jets of water from adjacent the lowermost portion of the vessel to the water line. 90 95

2. In combination with a vessel having a main propelling means, speed increasing means for the vessel including a pump mounted on the vessel, an intake pipe for the pump arranged to receive water from in front of the vessel, and outlet pipes having a plurality of spouts on each side of the vessel extending below the water line rearwardly of the bow of the vessel and arranged to expel the water from the pump in divergent streams directed rearwardly of the vessel. 100 105

3. In combination with a vessel having a main propelling means, speed increasing means for the vessel including a pump mounted on the vessel, an intake pipe for the pump arranged to receive water from in front of the vessel, and outlet pipes having a plurality of spouts on each side of the vessel extending below the water line rearwardly of the bow of the vessel and arranged to expel the water from the pump in divergent streams directed rearwardly of the vessel, said spouts having a plurality of spaced apertures extending from adjacent the lowermost portion of the boat to the water line. 110 115 120

4. In combination with a vessel having a main propelling means, speed increasing means for the vessel including a plurality of nozzles arranged below the water line at each side of the boat rearwardly of the bow, and means for forcibly expelling water 125 130

from said nozzles in divergent streams directed rearwardly of the vessel, said nozzles being provided with a plurality of spaced apertures extending from adjacent the lowermost portion of the vessel to adjacent the water line.

5. In combination with a vessel having a main propelling means, speed increasing means for the vessel including a pair of spaced nozzles arranged below the water line at each side of the boat rearwardly of the bow, and means for forcibly expelling water from said nozzles in divergent streams directed rearwardly of the vessel, one nozzle 10 of each pair being larger than the other and located closer to the widest portion of the boat.

6. In combination with a vessel having a main propelling means, speed increasing means for the vessel including a plurality of nozzles arranged below the water line at each side of the boat rearwardly of the bow, means for forcibly expelling water from 15

said nozzles in divergent streams directed rearwardly of the vessel, and a protective 25 casing surrounding said nozzles and having elongated apertures therein through which the expelled water issues.

7. In combination with a vessel having a main propelling means, speed increasing 30 means for the vessel including a plurality of nozzles arranged below the water line at each side of the boat rearwardly of the bow, means for forcibly expelling water from said spouts in divergent streams directed 35 rearwardly of the vessel, a protective casing surrounding said nozzles and having elongated apertures therein through which the expelled water issues, said casing being also formed with intake apertures forwardly 40 of the nozzles, and inclined vanes mounted on the casing above said last mentioned apertures.

In witness whereof I hereunto set my hand.

AUSTIN O. STANLEY.
